UNITED STATES PATENT OFFICE.

ABRAHAM MYERS, OF PHILADELPHIA, PENNSYLVANIA, ASSIGNOR TO HIMSELF, C. M. HALL, AND E. R. MYER, OF SAME PLACE.

IMPROVEMENT IN GAS APPARATUS.

Specification forming part of Letters Patent No. 43,079, dated June 7, 1864.

To all whom it may concern:

Be it known that I, ABRAHAM MYERS, of Philadelphia, Pennsylvania, have invented an Improvement in Gas Apparatus; and I do hereby declare the following to be a full, clear, and exact description of the same, reference being had to the accompanying drawings, and to the letters of reference marked thereon.

My invention consists in forming a communication between the hydraulic main of gas apparatus and a retort or retorts, substantially as described hereinafter, so that the gas-tar may be rendered available as gas-generating material without resorting to the tedious manipulation hitherto practiced for accomplishing the same purpose.

In order to enable others familiar with gas apparatus to make and use my invention, I will now proceed to describe its construction and operation.

On reference to the accompanying drawings, which form a part of this specification, Figure 1 is a front view of gas apparatus with my improvements; Fig. 2, a rear view, and Fig. 3 a side view.

Similar letters refer to similar parts throughout the several views.

A A' and B represent three retorts, mounted in brick-work C, in the usual manner; D, the stand-pipes communicating with the hydraulic main E, and the latter with a pipe, F, on the end of which is a tube, G, forming a communication between the said pipe F and the rear end of the retort B. It should be understood that the two lower retorts, A A', only are charged with coal or other gas-generating material. When distillation commences in these retorts, the gas, together with the tar, is conducted through the stand-pipes D D to the hydraulic main E, when the gas, passing through latter in the usual manner, becomes separated from the tar, and passes off through the pipe D, while the tar flows into the pipe F, and thence through the tube G into the rear end of the retort B, into

which is also introduced a jet of steam through the tube I. The object of this jet of steam is to prevent the tar from clogging and the tubes from corroding. The tar flows in a continuous stream into the retort, and as it passes through the same is converted into super-carbureted hydrogen gas, which, together with so much of the tar as is not converted into gas, passes through the stand-pipe into the hydraulic main, where the gas and tar will be again separated, the gas from the tar and that from the coal here uniting and passing off through the pipe D, and whatever tar may pass from the retort B meeting the tar which passes from the retorts A A' and both flowing into the retort B.

Tar has been heretofore used as a gas-generating material, both alone and in conjunction with other substances. The tar has hitherto, however, been permitted to flow into a well, and has been moved from thence to the retort by suitable implements, or has been taken from the well and mixed with other gas-generating substances, to be subsequently deposited in the retort, either of which operations demand very tedious manipulation, which my invention obviates, as the passage of the tar from the retorts to the hydraulic main and thence to the retort is continuous, and requires neither the assistance or watching of an attendant.

I claim as my invention and desire to secure by Letters Patent—

Forming a communication between the hydraulic main of gas apparatus and a retort or retorts, substantially as and for the purpose herein set forth.

In testimony whereof I have signed my name to this specification in the presence of two subscribing witnesses.

ABRAHAM MYERS.
